UNITED STATES PATENT OFFICE.

CLAUDE E. EMMONS, OF NEW YORK, N. Y., ASSIGNOR TO THE TEXAS COMPANY, OF NEW YORK, N. Y., A CORPORATION OF TEXAS.

TESTING DEVICE.

Application filed July 29, 1921. Serial No. 488,300.

This invention relates to testing devices, and it has special reference to flash cups such as are employed in determining the flash points of oil or the like.

Heretofore in the art it has been common to determine the flash points of oil by means of an open flash cup which is set into an air bath container to which heat is applied by some suitable agency, such as a Bunsen flame. In such apparatus the air bath container in which the flash cup is disposed, and upon which it rests, is usually constructed so as to surround the cup in such manner as to provide a space for the heating medium adjacent both the bottom and the peripheral side walls of the cup. With this construction there is a tendency for the most highly heated portions of the surrounding air bath to accumulate in the upper portion of the enveloping bath chamber whereby the contents of the cup is subjected to excessive local heating through the upper part of the peripheral wall thereof. This local heating results in the creation of the convection currents which prevent uniform temperature conditions throughout the fluid being tested.

Accordingly, it is an object of the present invention to provide a testing device of the above-indicated general character, which shall be so constructed and arranged that the fluid contained in the cup, and being tested, is uniformly heated and maintained at an even temperature throughout its mass.

To this end, the present invention contemplates a flash cup of the open type which is heated by means of an air bath container that is so constructed as to apply heat only to the bottom wall of the cup, thereby eliminating local heating and the resulting convection currents incident thereto. Furthermore, provision is made for gently agitating the fluid being tested in such manner as to insure the desired uniformity of temperature conditions throughout the fluid. This agitation is effected preferably by means of a plurality of stirring blades or arms that are carried by a vertical hollow shaft which is mounted for rotative movement and which carries a thermometer or other instrument by means of which the temperature of the fluid is ascertained.

The invention will be best understood by

reference to the accompanying drawing, which illustrates a preferred embodiment 55 of the invention and in which:

Fig. 1 is a view, partially in elevation and partially in section, of a testing device constructed in accordance with the present invention.

Fig. 2 is a sectional plan view of the device shown in Fig. 1, the section being taken along the section line 2—2 thereof.

Fig. 3 is an enlarged sectional view of the upper bearing of said device; and 65

Fig. 4 is an enlarged view in elevation, partially in section, of the lower bearing thereof.

Referring to the drawing, the testing device illustrated comprises a flash cup 10 70 having a bottom wall 11, a peripheral side wall 12 and an annular flange 13 projecting laterally from the upper portion of the cup. The cup is set into an air bath container 14 in concentric relation therewith, and is supported in position by the annular flange 13 which rests upon the upper edge 15 of the container. The dimensions of the cup and air bath container are so chosen that an air chamber or space 16 for the heating medium 80 is provided for the purpose of applying or transmitting heat to the cup 10 and its contents. The container is provided with an annular inwardly projecting flange or rib 17 which is adapted to make a relatively 85 tight joint with the cup 10, in order to prevent access of the heated air into that portion of the air chamber 16 which is adjacent to, and surrounds, the peripheral wall 12 of the cup, which portion also forms a dead air 90 space or heat-insulating chamber. By this means the application of heat is confined entirely to the bottom wall 11 of the cup, whereby local over-heating and the resultant convection currents incident to similar 95 testing devices of the prior art are eliminated. Moreover a heat insulating chamber is provided for preventing undue heat radiation through the peripheral wall of the cup. It will, of course, be understood that 100 although the partitioning flange 17 is illustrated as forming an integral part of the container it may equally well constitute a portion of the cup, or the component parts of the device may be otherwise constructed 105 so long as some means is provided for pre-

venting the application of heat to the peripheral walls of the cup, and for directing it entirely to the bottom wall thereof.

While the construction already described 5 may prove sufficiently effective for the purpose intended with certain grades of oil, uniform heating conditions throughout the mass of fluid being tested are best insured by providing suitable means for effecting a 10 gentle agitation of the cup contents. For this purpose, suitable stirring means preferably in the form of a plurality of stirring blades or arms 18, is provided. These stirring arms are located within the cup ad- 15 jacent the bottom wall thereof, being conveniently mounted upon a vertically extending rotatable shaft 19, the lower end of which rests in a central bearing 20 forming an integral part of the cup. The shaft is 20 preferably hollow and carries a suitable thermometer 21 disposed therein and rotated therewith, the thermometer being visible through an opening 22 provided in the cylindrical wall of the shaft. In order to 25 permit free access of the fluid being tested to the lower end or bulb of the thermometer, a plurality of apertures 22 are provided through the lower end of the shaft.

The rotatable shaft 19 is held in vertical 30 operating position by means of an upper bearing member or sleeve 23 which is held in a clamp 24 through an intermediate sleeve member 25 (see Fig. 3). The bearing 23 is preferably of glass and the sleeve 25 of 35 rubber or similar material, although any suitable substances may be employed. The clamp 24 forms a part of, or is carried by, an arm 26 projecting laterally from an up-right standard or supporting rod 27, to 40 which it is attached by an adjusting clamp 28. Above the bearing 23, suitable means in the form of a pulley 30 is provided, through the agency of which power from a suitable source may be applied for the purpose of effecting a slow rotative movement 45 of the shaft 19 and the stirring arms 18 mounted thereon. As shown, the pulley 30 is attached to the shaft through an intermediate bushing 31 of rubber or other suitable resilient material.

In utilizing the testing device described 50 for determining the flash points of oil or other fluids, it will be understood that the air bath container is subjected to heat from some suitable source, during which period heat is transmitted to the contents of the cup through the agency of the air bath. The shaft and attached stirring arms are slowly and continuously rotated throughout 55 the operation. In this way the contents of the flash cup is continuously and gently agitated whereby the entire contents of the cup is maintained at a uniform temperature. Inasmuch as the rotation of the shaft is 60 very slow, it is entirely practicable to make

readings of the thermometer during the operation although, if desired, the rotation of the shaft may be discontinued periodically to allow the thermometer to be read.

Of course, the invention should not be restricted to the particular illustrative embodiment set forth herein, as many modifications may be made without departing from the spirit of the invention, the true scope of which is defined in the appended claims. 70

Having disclosed the nature of the invention and described a specific embodiment thereof, what is claimed as new is:

1. In a testing device, the combination 80 with a flash cup, of a rotatable stirrer disposed therein for agitating the contents thereof, means for rotating said stirrer and a thermometer carried by and coincident with the axis of the stirrer and rotated with the stirrer for indicating the temperature of 85 the contents.

2. In a testing device, the combination 90 with a flash cup having a central bearing in the bottom thereof, of a rotatable hollow shaft having its lower end seated in said bearing, a plurality of stirring arms projecting from said shaft and disposed within said cup, and a thermometer mounted within the lower end of said hollow shaft.

3. In a testing device, the combination 95 with an open top flash cup having a central bearing in the bottom thereof, and a rotatable shaft seated in said bearing and provided with stirring arms, of an adjustable supporting device adjacent said flash cup 100 and carrying a bearing for the upper end of the stirrer shaft, and means for rotating said shaft in said bearing.

4. In a testing device, the combination 105 with a flash cup having a central bearing in the bottom thereof, and a rotatable stirring device comprising a vertical hollow shaft having its lower end resting in said bearing, of a thermometer disposed within the lower end of said hollow shaft and rotatable 110 therewith, said shaft being provided with a plurality of apertures adjacent its lower end to permit the free entrance of the cup contents into contact with said thermometer.

5. In a testing device, the combination 115 with a flash cup having a laterally projecting annular flange, and an air bath container surrounding said cup and in which the cup sets with its annular flange resting upon the upper edge of said container, of means 120 for preventing the exposure of other than the bottom wall of said cup to the heated air in said air bath container.

6. In a testing device, the combination 125 with a flash cup having a laterally projecting annular flange at substantially its upper end, and an air bath container surrounding said cup and in which the cup sets with its annular flange resting upon the upper edge 130 of said container and with its bottom and

side walls spaced from said container, of an annular partition between the side walls of said container and said cup and disposed in substantially the plane of the bottom wall of said cup whereby a heat insulating dead air space is provided to surround the side wall of said cup.

7. In combination, an outer cup-shaped receptacle having an inwardly projecting annular flange intermediate its top and bottom, and an open top flash cup having an

outwardly projecting annular flange adapted to be seated upon the upper end of the outer receptacle and with its lower periphery forming a seal with the inwardly projecting flange of the outer receptacle to form separated chambers around and beneath the flash cup. 10

In witness whereof I have hereunto set my hand and seal this 28th day of July, 1921.

CLAUDE E. EMMONS.
